Attorney

UNITED STATES PATENT OFFICE

MYRION TALBERT DICK, OF DES MOINES, IOWA

BLOTTING DEVICE

Application filed May 16, 1928. Serial No. 278,256.

The principal object of this invention is to provide a blotting device that readily absorbs liquid ink and the like from paper without the smearing or blurring of the same.

5 A further object is to provide a blotting device that is lifted and operated by only one hand.

10 A still further object of this invention is to provide a blotting device that may easily and quickly be refilled with new absorbent blotting material.

15 A still further object of this invention is to provide a blotting device that is noiseless in operation.

20 A still further object of this invention is to provide a blotting device that will not scratch or mar the supporting surface upon which it may be at rest.

25 A still further object of this invention is to provide a blotting device that remains stationary upon the paper to be blotted while the movable portion is being reciprocated.

30 A still further object of this invention is to provide a blotting device that is refined in appearance by having its movable carriage portion inclosed and out of sight.

35 A still further object of this invention is to provide a blotting device having a fixed portion and a movable portion which have no movement relative to each other when the device is lifted from a supporting surface.

40 My invention consists in the construction, arrangement and combination of the various parts of the device, whereby the objects contemplated are attained as hereinafter more fully set forth, pointed out in my claims and illustrated in the accompanying drawings, in which:

45 Fig. 1 is a perspective view of my device already for use with an ordinary pen supported in the handle member.

50 Fig. 2 is a side sectional view taken on line 2-2 of Fig. 1 of my blotting device and illustrates the manner in which the rollers depress the blotter upon the ink to be absorbed.

55 Fig. 3 is a cross sectional view of the invention taken on line 3-3 of Fig. 2 and more fully illustrates its interior construction.

60 The use of a piece of blotting paper for ink absorbing purposes is not only unsightly

after use, but is hard to find and pick up with the fingers and requires two hands to operate. When a blotter is so used with the two hands, a rolling effect is given to the wet ink, thereby blurring the penmanship on the paper. 55 I have overcome these disadvantages as will be appreciated by those skilled in the art.

60 I have designated the frame or housing of my device by the numeral 10, having its bottom open. Integrally formed on the marginal edge of each of the two longitudinal sides of the housing 10 is an inwardly extending flange 11, as shown in Fig. 2 and Fig. 3. Loosely resting upon these two flanges, inside the housing 10 and inclosing the bottom 65 thereof is a sheet of absorbing material 12. The cut away portions 13 in each end of the housing 10 permits the entrance of the thumb and finger for the grasping of the absorbent material 12 for the easy removal or replace- 70

75 ment of the same. This frame or housing may be made of any suitable material such as light sheet metal or celluloid compositions and is of rectangular construction so that it may easily be placed over any character strokes that are adjacent the hinge portion of a check book or the like. In order to hold the housing a slight distance from the surface of the furniture upon which it may be resting, I have provided the resilient feet 14. These 80 feet may be held in place by cups 15. It will be found that these resilient supports also prevent the housing and blotter from sliding upon the paper to be blotted while the carriage of the device is being reciprocated. 85

90 The numeral 16 designates a longitudinal slot in the top of the housing 10, as shown in Figs. 1 and 3. Secured to the two ends of the housing 10, slightly below and inside the housing 10 is the bridge member 17, as shown in Fig. 2 and Fig. 3. Embracing this bridge member is the carriage member of the device designated by the numeral 18 and of channel iron construction in cross section. Journaled in the two end portions of the carriage member 18, spaced apart and transverse the longitudinal axis of the housing 10 are the two rods 19 and 20.

95 Around each of these rods is a roller 21 of 100 suitable resilient material. It should here be

noted that each of the rollers are so positioned that they extend beyond the member 18, thereby being capable of engaging the two ends of the housing 10 and acting as bumpers for eliminating undesirable noise. These resilient rollers also serve a similar function when the complete device is lifted by the member 18 by noiselessly engaging the rack 22 secured to the underside of the bridge member 17. The purpose of the rack member 22 is to prevent the carriage from moving relative to the housing 10 when the device is lifted. When the device is operated, the resilient rollers naturally drop down upon the absorbent material and out of engagement with the rack 22. The numeral 23 designates a handle member secured to the carriage 18 and extending upwardly and through the slot 16. It is with this handle that the device is lifted and operated. By the bridge member 17 being directly below the slot 16, all of the movable portions inside the housing 10 will be out of sight. This bridge member should be of suitable rigid material and to prevent the top surface from being scratched or disfigured by the carriage 18 coming in contact with the same, I have provided the projections 24 on the under side of the carriage member 18, so located that they are capable of engaging the bridge member near its marginal edges.

By this construction, the only marring that can possibly be done to the bridge member must be done by the projections 24 and will be at a point not adjacent the opening 16 and therefore, out of sight.

If it is desired, a well 25 may be formed in the handle member, as shown in Fig. 1 to accommodate the end of an ink pen.

To operate the device, it is merely necessary to lift the same by the handle member 23 and place the housing 10 over the character strokes to be blotted and move the handle member 23 backwardly and forwardly relative to the housing 10, causing the resilient rollers 21 to roll upon the top surface of the absorbent material 12 and to press the same upon the wet ink to be blotted. There is no danger of blurring the penmanship, as the blotter 12 is placed in a flat condition over the ink to be blotted. The complete operation is noiseless and requires only one hand.

When the blotting paper 12 becomes too worn or soiled for further successful use, it may be easily removed in a moment's time and a new blotter inserted.

Some changes may be made in the construction and arrangement of my improved blotting device without departing from the real spirit and purpose of my invention and it is my intention to cover by my claims any modified forms of structure or use of mechanical equivalents which may be reasonably included within their scope.

I claim:

1. In a device of the class described, a housing member open at its bottom and having a longitudinal slot in its top, absorbent material for inclosing said bottom, a bridge member of greater width than the width of said slot inside said housing and at a point below said slot, a U-shaped member extending around the sides and top of said bridge member, a handle member secured to said U-shaped member and extending through said slot, a plurality of roller members journaled in said U-shaped member and below said bridge member, and a rack secured to the under side of said bridge member, capable of engaging said rollers when the device is lifted by said handle. 70 75 80

2. In a device of the class described, a housing member open at its bottom and having a longitudinal slot in its top, absorbent material for inclosing said bottom, a bridge member of greater width than the width of said slot inside said housing and at a point below said slot, a U-shaped member extending around the sides and top of said bridge member, a handle member secured to said U-shaped member and extending through said slot, a plurality of roller members journaled in said U-shaped member and below said bridge member, a rack secured to the under side of said bridge member, capable of engaging said rollers when the device is lifted by said handle, and projections formed on the under side of said U-shaped member. 90 95 100

3. In a blotting device, a housing open at its bottom and having a longitudinal slot in its top, a means for securing a blotting paper in the bottom of said housing, a bridge member of greater width than the width of said slot inside of said housing and at a point below said slot, a U-shaped member embracing said bridge member, a plurality of rollers secured to the free end of said U-member, and a handle member secured to said U-member and extending through said slot. 105 110 115

4. In a device of the class described, a housing member open at its bottom and having a longitudinal slot in its top, absorbent material for inclosing said bottom, a bridge member inside said housing and at a point below said slot, a U-shaped member extending around the sides and top of said bridge member, a handle member secured to said U-shaped member, extending through said slot and having a well formed therein capable of accommodating an ink pen, a plurality of roller members journaled in said U-shaped member and below said bridge member, and a rack secured to the under side of said bridge member capable of engaging said rollers when the device is lifted by said handle. 120 125 130

5. In a device of the class described, a housing member open at its bottom, absorb-

ent material for inclosing said bottom and having a longitudinal slot in its top, a bridge member inside said housing and at a point below said slot, a U-shaped member extending around the sides and top of said bridge member, a handle member secured to said U-shaped member and extending through said slot, a plurality of roller members journaled in said U-shaped member and below said bridge member, and projections formed on the underside of said U-shaped member.
